UNITED STATES PATENT OFFICE.

JULIUS MEREDITH, OF CHICAGO, ILLINOIS, ASSIGNOR OF ONE-HALF TO DANIEL P. TETER,
OF CHICAGO, ILLINOIS.

ROTARY STAMPING DEVICE.

1,356,386.

Specification of Letters Patent. Patented Oct. 19, 1920.

Application filed March 27, 1920. Serial No. 369,248.

To all whom it may concern:

Be it known that I, JULIUS MEREDITH, a citizen of Hungary, (who has applied for United States citizenship,) and a resident 5 of Chicago, in the county of Cook and State of Illinois, have invented a new and useful Improvement in Rotary Stamping Devices, of which the following is a full, clear, and exact description.

10 My invention relates to improvements in rotary stamping devices, and it consists in the combinations, constructions and arrangements herein described and claimed.

An object of my invention is to provide a 15 novel form of rotary stamping device for stamping letters, numerals, and the like into metals.

A further object of my invention is to provide a device of the type described in 20 which means is provided for adjusting the die holding mechanism with respect to the articles to be stamped so that impressions of different characters can be neatly and quickly stamped upon such articles.

25 A further object of my invention is to provide a device of the type described in which means is provided to permit the use of dies bearing characters varying in size.

A further object of my invention is to 30 provide in a device of the type described a novel means for moving the portion of the device supporting the articles in which impressions are to be stamped to insure proper spacing and arrangement of such impressions.

Other objects and advantages will appear in the following specification, and the novel features of the invention will be particularly pointed out in the appended claims.

40 My invention is illustrated in the accompanying drawings, forming part of this application, in which—

Figure is a front face view of the device, a portion being broken away and other portions being shown in section,

Fig. 2 is a side elevation of the device,
Fig. 3 is a section along the line 3—3 of

Fig. 1,

Fig. 4 is an enlarged perspective view of 50 a die used in the device,

Fig. 5 is a perspective view of a portion of the device,

Fig. 6 is an enlarged perspective view of another portion of the device,

Fig. 7 is a perspective view of still another portion of the device, 55

Fig. 8 is an enlarged detailed view partly in section of a fragmentary portion of the device.

In carrying out my invention, I provide a base 1. An upright supporting frame 2 is formed integral with the base 1. The upright supporting frame 2 is formed with central channels 3 and 4 extending through the upper portion thereof and intersecting 65 at right angles. A guide member 5 (see Figs. 3 and 7) is slidably disposed within the guideway 4 and is maintained in horizontal position by a washer 6 which is carried upon a stud bolt 7 which is screwed 70 into a threaded opening 8 in the end of the guide member 5 and which is maintained in position by a nut 9 which is screwed on the end of the stud bolt 7. A recess 10 in the guide member 5 is adapted to receive 75 the lower end 11 of the connecting rod 12 which is pivoted therein by a pin 13 which is inserted through an opening 14 in the guide member 5. The upper end 15 of the connecting rod 12 is pivotally secured to an 80 eccentric portion 16 which is formed integrally with a shaft 17 and serves as a crank.

The shaft 17 is journaled in a housing or 85 crank case 18 which is of the form illustrated in Fig. 5 of the accompanying drawings. The housing 18 is slidably disposed in the guide ways 3 and 4 and is maintained in horizontal position by a washer 19 which is carried upon a stud bolt 20. The stud bolt 20 is screwed into a threaded opening 90 21 in the housing 18 and a nut 22 screwed on the end of the stud bolt 20 maintains the washer 19 in position.

The housing 18 is formed with a vertically extending threaded opening 23 adapted to receive a threaded rod 24 which extends therethrough and which has its lower end inserted through an opening 25 in the guide member 5. The upper end of the threaded rod 24 extends through a plate 26 100 which is bolted to the frame 2 by the bolts 27. A bevel gear 28 is rigidly secured to the upper end of the threaded rod 24. A second bevel gear 29, carried at the end of a rod 30 which is journaled in a bearing 31, 105 is in mesh with the bevel gear 28. The bearing 31 is formed integrally with the plate 26. An arm 32 is rigidly connected

with the end of the rod 30 and carries at its other end a handle 33. It will thus be seen that the guide member 5 and the housing 18 may be shifted in a vertical plane by operation of the arm 32.

- Referring now to Fig. 7, it will be noted that the guide member 5 has an integral laterally extending portion 34. A pin 35 is inserted through an opening in the end of 10 the laterally extending portion 34. A spring 36 is held between a pin 37 inserted through the pin 35 adjacent its end and the end of the laterally extending portion 34. It is therefore possible to partly withdraw the 15 pin 35 against the tension of the spring 36 from the opening in the end of the laterally extending portion 34. The pin 35 has a function which will be hereinafter set forth.

The guide member 5 has also an integral 20 cylindrical extension 38. A sleeve 39 is mounted to rotate upon the cylindrical extension 38. A disk 40 is rigidly mounted upon the sleeve 39, as best seen in Fig. 3. A second disk 41 is feathered upon the sleeve 25 39 and may be moved therealong, but is prevented from rotating by a feather 42. The sleeve 39 is maintained in position upon the cylindrical extension 38, by a lock nut 43, and a bolt 46. The lock nut 43 is 30 screwed on the threaded end 44 of the sleeve 39 and the bolt 46, which is loosely disposed in the opening 45 through the lock nut 43, is screwed in a threaded opening 47 provided in the end of the cylindrical extension 35 38. It will thus be noted that the disk 41 is also maintained in position by the lock nut 43 and the bolt 46. An annular recess 48 is 40 provided in the outer face of the disk 40 around its outer edge. A plurality of openings 49, spaced at equal distances apart, are formed through the disk 40 adjacent its outer edge. The openings 49 register with openings 50 which extend partly through the disk 41. Stub shafts 51 are disposed 45 within the openings 49 and 50, as clearly shown in Fig. 3.

A die 53, which is of the shape shown in Fig. 4, is keyed to each of the stub shafts 51 and is disposed between the disks 40 and 50 41. It will be noted that the die 53 has a plurality of flattened faces formed upon its periphery and that a character 55 is placed upon each flattened face. Each flattened face 54 has a character 55 of a different size 55 from that found upon the other flattened surfaces of the die.

A ring gear 56 is disposed within the annular recess 48 and has its outer rim in mesh with gears 52 which are rigidly secured to 60 the stub shafts 51. A shouldered pin 57 is inserted through registering openings in the disks 40 and 41 and has a gear 59 rigidly secured thereto. The gear 59 is arranged within a recess 60 in the face of the disk 40 65 to mesh with the inner edge of the ring gear

56. An end of the shouldered pin extends through a washer or lock nut 61 which is non-circular in form and is embedded in the inner face of the disk 40. The pin 57 is then maintained in position in any approved 70 manner as by upsetting the end thereof or by having a cotter pin (not shown) inserted through its end.

A hexagonal head 58 formed integrally with the pin 57 provides a means for readily operating the gears 59, 56, and 52 to revolve the dies 53 and thereby change the size of the characters which are in position to be stamped into articles as desired. An indicator arm 62 is connected to the head 75 58 and when the latter is turned, the indicator arm will be moved arcuately along the scale 63 to indicate the size of the character that is then in position to be stamped upon the work.

A provision of a satisfactory means for moving the work supporting portion of the device to insure the impressions being properly spaced and arranged in the work adds greatly to the efficiency of the device. I 90 therefore provide a cam member 64 which is rigidly secured to the end 65 of the shaft 17. A roller 66 carried at the end of the rod 67 engages the cam 64. A plate 68 is secured to the rod 67 by means of a screw 69. 95 Springs 70 are disposed between the plate 68 and a support 71 which is formed integrally with a plate 72 and maintain the roller 66 in engagement with the cam 64. The plate 72 is secured to the frame 2 by means 100 of screws 73. A stud bolt 75 is screwed into the rod 67 at its lower end and is slidably disposed in a slot 74 provided in the upper end of the second rod 77. A nut 76 upon the stud bolt 75 serves to hold the upper end 105 of the rod 77 in slidable relation with the lower end of the rod 67. The lower end of the rod 77 is flattened and is pivotally secured to the center of a disk 78. The lower end of the rod 77 has a lateral extension 79 110 provided with an opening 80 formed there-through. The opening 80 registers with one of a plurality of openings 81 formed through the disk 78 and a tapered pin (not shown) may be inserted through the registering 115 openings to prevent the disk 78 from being rotatably moved. The disk 78 has inclined cam members 82 spaced around its outer edge. The cam members 82 taper from the center of the disk toward the outer edge and 120 vary in height. An arm 83, pivoted at 84 to the base 1, has a roller 85 in contact with one of the cam members 82.

It will be understood that the disk 78 may be rotated at will to bring any one of the 125 cam members 82 into engagement with the roller 85 and that only one of such cam members is in operative engagement with the roller during the operation of the device. A spring 86 (see Fig. 8) maintains 130

the roller 85 in contact with the cam members 82.

A pawl 87, which is inserted in a slot in the other end of the arm 83, engages the 5 teeth 88 of a rack 89, the pawl being so held by the spring 90. A work supporting table 92 has a tapered base 93 slidably disposed in a recess 91 in the base 1. The rack 89 is inserted through an opening 94 in the work 10 supporting table 92 and is held in position by means of a collar 96. An end plate 98 is secured to the work supporting table 92 by screws 99. The collar 96 projects there-through, as clearly shown in Fig. 2, and a 15 tapered pin 97 inserted through a notch 101 in the collar 96 into the end plate 98 prevents the rotation of the rack 89. Teeth 88 are provided upon a plurality of sides of the rack 89 and vary in size in direct proportion to the size of the cam members 82.

A wheel or handle 95 upon the end of the rack 89, as illustrated in Fig. 1, provides a means for adjusting the rack 89 so that the pawl 87 will engage teeth of the proper size 25 to move the work supporting table the required distance for proper spacing of the impressions. A cotter pin 100 inserted through the end of the rack, as shown in Fig. 8, holds the collar 96 in position. The 30 notches 101 in the collar 96 indicate the side of the rack that is being engaged by the pawl.

From the foregoing description of the various parts of the device, the operation 35 thereof may be readily understood. The disks 40 and 41 are rotated until the die bearing the character selected is directly above the work supporting table 92. The pin 35, which has been partly withdrawn 40 from the opening in the end of the member 34 against the tension of the spring 36, is permitted to enter one of the openings 49 to prevent further rotation of the disks 40 and 41. The die selected will be lowered into 45 contact with an article placed upon the work supporting table when the arm 32 is operated. The crank mechanism is then operated by means of an arm 102 and a handle 103 and an impression is stamped in the 50 work. Operation of the crank shaft 17 operates the rods 67 and 77, thereby moving the work supporting table from right to left. The impressions will therefore be uniformly stamped in and arranged upon the 55 work placed upon the work supporting table. It is obvious that forms of the device varying from that illustrated in the accompanying drawings may be provided without departing from the scope and spirit of 60 my invention as set forth in the foregoing specification and outlined more particularly in the appended claims.

I claim:

1. A rotary stamping device comprising 65 a supporting frame having a guide-way

formed therein, a guide member slidably disposed in said guide-way, a cylindrical extension formed integrally with said guide member, die holding means rotatably mounted upon said cylindrical extension, means 70 for locking said die holding means in a desired position, a work supporting table slidably disposed in said supporting frame, means for moving said die holding means toward and away from said work supporting table, other means for operating said die holding means to stamp an impression in work placed upon said work supporting table, and means operated by said last named means for moving the work supporting table to insure proper spacing between and arrangement of the impressions stamped in the work.

2. A rotary stamping device comprising a base, a supporting frame formed integrally therewith, said frame having central guide-ways formed in its upper end to intersect at right angles, a guide member slidably disposed in one of said guide-ways, a cylindrical extension formed integrally with said 85 guide member and projecting laterally with respect thereto, circular die holding means 90 rotatably mounted upon said cylindrical extension, means for locking said circular die holding means in a desired position, a plurality of dies arranged at spaced distances 95 around the periphery of said circular die holding means, each die having a plurality of characters varying in size arranged around its edge, means for simultaneously 100 adjusting said dies to selectively arrange said different sized characters in position to be impressed in work, a work supporting table slidably disposed in said supporting frame, means for moving said die holding 105 means toward and away from said work supporting table, other means for operating said die holding means to stamp an impression in work placed upon said work supporting table, and means operated by said 110 last named means for moving the work supporting table to insure proper spacing between and arrangement of the impressions stamped in the work.

3. A rotary stamping device comprising a base, a supporting frame formed integrally therewith, said frame having central guide-ways formed in its upper end to intersect at right angles, a guide member slidably disposed in one of said guide-ways, a cylindrical extension formed integrally with said 115 guide member and projecting laterally with respect thereto, circular die holding means 120 rotatably mounted upon said cylindrical extension, means for locking said circular die holding means in a desired position, a plurality of dies arranged at spaced distances 125 around the periphery of said circular die holding means, each die having a plurality of characters varying in size arranged 130

- 4
- around its edge, means for simultaneously adjusting said dies to selectively arrange said different sized characters in position to be impressed in work, means operated by 5 said last named means for indicating the size of the characters so arranged, a work supporting table slidably disposed in said supporting frame, means for moving said die holding means toward and away from 10 said work supporting table, other means for operating said die holding means to stamp an impression in work placed upon said work supporting table, and means operated by said last named means for moving the 15 work supporting table to insure proper spacing between and arrangement of the impressions stamped in the work.
4. A rotary stamping device comprising a base, a supporting frame formed integrally therewith, said frame having central guide-ways formed in its upper end to intersect at right angles, a guide member slidably disposed in one of said guide-ways, a cylindrical extension formed integrally with said 20 25 30 35 40 45 50 55 60 65 70 75 80 85 90 95 100 105 110 115 120 125 130 guide member and projecting laterally with respect thereto, a sleeve rotatably mounted upon said cylindrical extension, a disk mounted upon the inner end portion of said sleeve and rigidly secured thereto, a second disk feathered upon the sleeve and slidably therealong, means for maintaining said second named disk at a spaced distance from said first named disk, means for locking said disks in a desired position with respect to said guide member, thereby preventing rotatable movement of said disks, a plurality of dies arranged between the adjacent faces of said disks to project beyond the peripheral portions thereof, said dies being spaced apart and each die having a plurality of characters varying in size arranged around its edge, means for maintaining said dies in operative position between said disks, means for simultaneously adjusting said dies to selectively arrange said different sized characters in position to be impressed in the work, a work supporting table slidably disposed in said supporting frame, means for moving said die holding means toward and away from said work supporting table, other means for operating said die holding means to stamp an impression in work placed upon said work supporting table, and means operated by said last named means for moving the work supporting table to insure proper spacing between and arrangement of the impressions stamped in the work.
6. A rotary stamping device comprising a base, a supporting frame formed integrally therewith, said frame having central guide-ways formed in its upper end to intersect at right angles, a guide member slidably disposed in one of said guide-ways, a cylindrical extension formed integrally with said guide member and projecting laterally with respect thereto, a sleeve rotatably mounted upon said cylindrical extension, a disk mounted upon the inner end portion of said sleeve and rigidly secured thereto, a second disk feathered upon the sleeve and slidably therealong, means for maintaining said second named disk at a spaced distance from said first named disk, means for locking said disks in a desired position with respect to said guide member, thereby preventing rotatable movement of said disks, a plurality of dies arranged between the adjacent faces of said disks to project beyond the peripheral portions thereof, said dies being spaced apart and each die having a plurality of characters varying in size arranged around its edge, means for maintaining said dies in operative position between said disks, means for simultaneously adjusting said dies to selectively arrange said different sized characters in position to be impressed in work, means operated by said last named means for indicating the size of the characters so arranged, a work supporting table slidably disposed in said supporting frame, means for moving said die holding means toward and away from said work supporting table, other means for operating said die holding means to stamp an impression in work placed upon said work supporting table, and means operated by said last named means for moving the work supporting table to insure proper spacing between and arrangement of the impressions stamped in the work.
5. A rotary stamping device comprising a base, a supporting frame formed integrally therewith, said frame having central guide-ways formed in its upper end to intersect at right angles, a guide member slidably disposed in one of said guide-ways, a cylindrical extension formed integrally with said guide member and projecting laterally with respect thereto, a sleeve rotatably mounted 65 70 75 80 85 90 95 100 105 110 115 120 125 130

tively arrange said different sized characters in position to be impressed in the work, a work supporting table slidably disposed in said supporting frame, means for moving 5 said die holding means toward and away from said work supporting table, other means for operating said die holding means to stamp an impression in work placed upon said work supporting table, and means 10 operated by said last named means for moving the work supporting table to insure proper spacing between and arrangement of the impressions stamped in the work.

7. A rotary stamping device comprising 15 a base, a supporting frame formed integrally therewith, said frame having central guide-ways formed in its upper end to intersect at right angles, a guide member slidably disposed in one of said guide-ways, 20 a cylindrical extension formed integrally with said guide member and projecting laterally with respect thereto, a sleeve rotatably mounted upon said cylindrical extension, a disk mounted upon the inner end 25 portion of said sleeve and rigidly secured thereto, a second disk feathered upon the sleeve and slidable therealong, means for maintaining said second named disk at a spaced distance from said first named disk, 30 means for locking said disks in a desired position with respect to said guide member, thereby preventing rotatable movement of

said disks, a plurality of dies arranged between the adjacent faces of said disks to project beyond the peripheral portions 35 thereof, said dies being spaced apart and each die having a plurality of characters varying in size arranged around its edge, means for maintaining said dies in operative position between said disks, said means 40 comprising a plurality of stub shafts for the dies, each having its ends inserted in registering openings provided in the adjacent faces of said disks, the openings being formed to extend entirely through said first 45 named disk and partly through said second named disk, means for simultaneously adjusting said dies to selectively arrange said different sized characters in position to be impressed in the work, means operated by 50 said last named means for indicating the size of the characters so arranged, a work supporting table slidably disposed in said supporting frame, means for moving said die holding means toward and away from 55 said work supporting table, other means for operating said die holding means to stamp an impression in work placed upon said work supporting table, and means operated by said last named means for moving 60 the work supporting table to insure proper spacing between and arrangement of the impressions stamped in the work.

JULIUS MERAY.
